UNITED STATES PATENT OFFICE.

EDWIN A. GASKILL AND JOSEPH F. GASKILL, OF LANEVILLE, WEST VIRGINIA.

TOWER-SPAR.

1,083,277.

Specification of Letters Patent.

Patented Jan. 6, 1914.

Application filed April 3, 1913. Serial No. 758,636.

To all whom it may concern:

Be it known that we, EDWIN A. GASKILL and JOSEPH F. GASKILL, citizens of the United States, both residing at Laneville, county of Tucker, and State of West Virginia, have jointly invented an Improved Tower-Spar, of which the following is a specification.

This invention, broadly stated, relates to spars used in connection with overhead cable way systems, and has more particular relation to the providing of a novel form of spar particularly adapted for use in conjunction with the overhead skidding of logs.

The principal object of the present invention, may be said to reside in the providing of a tower spar, the parts of which have telescopic relation with one another whereby the spar may be readily raised and lowered vertically with respect to the tower, means being present to hold the spar in raised and lowered position.

A further object of the present invention, is to provide a relatively fixed tower provided with a guide way through which is adapted to be moved vertically, a tubular spar capable of rotatable movement around its own axis, said vertical and rotary movements of the spar being possible, irrespective of its position without the necessity of casting loose the guy ropes and main cable from the spar cap.

A still further object of the present invention is to provide a tower spar mounted upon traction wheels, whereby the same may be readily moved from place to place, the parts of said tower spar having telescopic relation with one another.

A still further object of the present invention, is to provide a tower spar, provided with a platform the parts being so arranged, connected and constructed that the spar may be lowered vertically with respect to the tower; so that, workmen on the platform, may conveniently have access to the spar cap without casting loose the main cable and guy ropes and other tackle usually secured to a spar cap.

A still further object of the present invention, is to provide a tower spar of novel construction, whereby simplicity, efficiency and cheapness in the overhead skidding of logs is effected.

Other and further objects of the present invention, relate to the providing of general details of construction and arrangement of parts.

The invention consists of the improvements hereinafter described and finally claimed.

The nature, characteristic features and scope of the invention will be more readily understood from the following description taken in connection with the accompanying drawings forming part hereof and in which:

Figure 1, is a view in front elevation of a tower spar embodying the invention, the spar being shown in raised or operative position, Fig. 2, is a view in plan partly sectioned of the tower spar said figure being a section taken approximately on the line 2—2 of Fig. 1, Fig. 3, is a similar view taken approximately on the line 3—3 of Fig. 1, Fig. 4, is a similar view taken approximately on the line 4—4 of Fig. 1, Fig. 5, is a fragmentary view in section, illustrating the manner of sustaining the spar in raised position, Fig. 6, is a fragmentary view in elevation illustrating the spar in its lowered position, and Fig. 7, is a detail view of one of the shiftable bolts shown in Fig. 5.

While the tower spar of the present invention is particularly adapted for use in conjunction with the overhead skidding of logs, any reference herein appearing to such use, is merely for illustrative purposes as the tower spar of the invention is adaptable to various overhead cable way systems.

Referring to Fig. 1, of the drawings, 10, designates a generally rectangular skeleton-like relatively fixed supporting structure or tower of any practical construction which carries at its top a fixed platform 11. For convenience and easy handling, the tower 10, is shown as being fixed upon a flat car 12, mounted upon traction wheels 13. Within the tower 10, and having fixed relation therewith, are vertically disposed rails 14, shown in the drawings as being I-beams which form a guide way. As clearly shown in Fig. 1, this guide way is arranged intermediate the top and bottom of the tower 10. Connecting the bottoms of the rails 14, are plates, channel beams or

other suitable mediums 15, forming a stop or rest, the purpose of which will presently appear.

Within the tower 10, and immediately adjacent the top of the guide way, is located a sustaining device for retaining in operative position the spar to be presently described. In the specific instance shown, this sustaining device comprises a pair of horizontally disposed endwise shiftable bolts 16, see Figs. 3, and 5. Each bolt is slotted upon its underside to receive a toothed rack 17, pinions 18, mounted upon a suitably supported shaft 19, being present for intermeshing with said racks 17.

In order to properly support and keep the bolts in alinement, a box-like structure 20, open top and bottom and having secured to one side sleeves or guides 20^a, is present. This structure has fixed relation with the tower 10, and is provided with apertures 21, in its side walls through which said bolts work and the sleeves 20^a, are slotted to accommodate the pinions 18. A convenient way of operating the bolts 16, is by means of a sprocket chain 22, which connects with a sprocket wheel 23, fixed to the shaft 19, and a sprocket wheel 24, provided with an operating handle which wheel is journaled to the tower 10, adjacent the floor of the car 12.

Having telescopic relation with and positioned for vertical movement through the guide way within the tower 10, is a combined base, spar and cap, which parts are designated respectively 25, 26, and 27. For convenience, these parts will hereinafter be termed the spar. In the specific instance shown in the drawings, this spar is constructed in accordance with the base, patented to us under date of November 19, 1912, and numbered 1,044,771; the spar, as shown and described in our application, Serial No. 686,183, filed March 25, 1912, and the cap, as shown and described in our application, for Letters Patent, Serial No. 703,506, filed June 13, 1912. Obviously, however, other forms of spars including bases and caps may be advantageously used if desired. In order to raise and lower the spar with respect to the tower, practice has dictated that the following parts are efficient:—a pair of pulley blocks 28, see Figs. 1, and 2, are secured to the tower 10, preferably immediately beneath the platform 11, at points diagonally opposite one another through which pulley blocks, is passed a sling 29, the free ends of which are suitably secured as at 30, to the spar 26, the bight of said sling connecting with a three sheave fall block 30^a, which block and a similar block 31, secured to the car 12, are reefed by a fall line 32, which line in turn passes to the drum of a skidding engine, not shown in the drawings. By means of

this connection of parts, the spar 26, may be readily raised to operative position as shown in Fig. 1. Located upon the car 12, directly beneath the tower 10, is a tensioning engine 33, passing from the drum of which, through an opening in the base 25, and up through the tubular spar 26, and thence over a sheave 34, in the cap 27, is the main cable 35, which passes to a suitable anchorage not shown. Immediately behind the sheave 34, and connected to the spar, are two suitably reefed four sheave fall blocks 35^a, connecting with a split anchorage. This rigging is to counter-act the strain upon the spar of the main cable 35. Passing from guy drums 37, arranged at the tower corners, upon the floor of the car 12, are guy ropes 38, which pass through openings 39, in the platform 11, to and over sheaves 40, carried by the cap 27, and thence to suitable anchorages not shown.

When the spar 26, is in lowered position, that is with its base 25, resting upon the plates 15, at the bottoms of the guide way, see Fig. 6, riggers working upon the platform 11, can readily adjust to position the main cable 35, the guy ropes 38, and other rigging required at the spar top. The skidding engine may then be operated to elevate the spar to the position shown in Fig. 5, through the connections hereinbefore described. In this elevated position of the spar, the sprocket wheel 24, is operated to shift to place beneath the spar base 25, through the mechanism described, the bolts 16. Thus, when the various guy ropes are tightened, the spar 26, is operatively positioned. When it be desired to move the tower spar from one position to another, the spar 26, is lowered, as will be readily understood, to the position shown in Fig. 6, without disconnecting from the spar cap, the main cable or guy ropes. The lowering of the spar 26, throws the center of gravity of the tower spar as a whole relatively low and makes it perfectly safe and practicable to move the car 12, to desired position. It may be stated at this time, that by the use of the spar construction as set forth in our said patent and applications for patents, the spar may be rotated around its own axis and with respect to the guy ring 31, without interfering with the main cable or guy ropes at the spar top which obviously is advantageous.

Having now described the nature and objects of the invention and how the same is to be operated, what we claim as new and desire to obtain by Letters Patent is:

A portable tower spar for use in an overhead cable-way system comprising a tower, a spar, including its complemental base and cap operatively fitted as a unit for up and down movement within the tower, said spar being constructed to permit of the free pas-

sage therethrough of a main cable, means for elevating said spar, means operatively connected with the tower capable of being shifted into the path of the spar for retaining same in elevated position and means independent of the shiftable means connecting with the spar cap for properly alining the spar in its elevated position.

In testimony whereof, we have hereunto signed our names.

EDWIN A. GASKILL.
JOSEPH F. GASKILL.
